AUTOMATIC CASE SHIFT

Paul M. Rainey, Martinsville, N. J., assignor to
 Combination Selector Company, Glen Ridge,
 N. J., a corporation of New Jersey

Application January 20, 1942, Serial No. 427,420

8 Claims. (Cl. 197—73)

This invention relates to new and useful improvements in case shifting mechanisms for writing machines, such as typewriters, stencil cutting machines, embossing machines, etc.

The object of the present invention is to provide automatic case shifting in response to certain predetermined operations thus increasing the output of the machine and reducing the effort required of the operator. In the specific embodiment disclosed, the return of the carriage to the beginning of a new line and the operation of the space bar or key causes the machine to shift to upper case and, after a type bar has been actuated, back to lower case.

The invention is particularly applicable to addressing or like operations. For example in the following address:

Mr. John Doe
 #1620 James St.
 New York City, N. Y.

there are 39 printed characters, 11 of which are upper case characters. Also note that each upper case character is either the first character of a line or follows a space.

It is therefore a further object to furnish a more efficient means for keyboard operators who write addresses and like copy on typewriters, stencil cutters, embossing machines, etc.

In the present exemplification of the invention, in addition to the usual manually operable case shift, an electromagnetically controlled case shift may be switched into operation so as to function upon the return of the carriage to the beginning of a line and each operation of the space bar. The electromagnetic shift can be operated also in response to each actuation of a special key and disabled upon the actuation of another key. The invention is disclosed as an attachment which may be readily combined with existing typewriters.

These and other features of the invention will more clearly appear from the following description of an embodiment thereof and the appended claims.

In the drawings, Fig. 1 is a side elevation of so much of a typewriter as is necessary for an understanding of the invention;

Fig. 2 a side elevation of a detail at the back of the typewriter;

Fig. 3 a section along lines 3—3 of Fig. 2;

Fig. 4 a side elevation of the shift operating magnet;

Fig. 5 a section along lines 5—5 of Fig. 4;

Fig. 6 a plan view of part of the typewriter keyboard; and

Fig. 7 a diagrammatic illustration of the circuit arrangement.

The typewriter (see Fig. 1) consists of the usual carriage 1 including a platen 2 mounted between two end brackets 68 (one shown), which slides on ball bearings 3. By means of a case shift key 4 (Fig. 6), the carriage may by means (not fully shown) be lifted into the position indicated by dotted lines. In the normal position, lower case indicia in types like 5 will strike against the platen 2 when the type is actuated by a key like 6 through the agency of the customary type bars and other linkage. When raised, the upper case indicia strike the platen 2 in the proper alignment.

15 The carriage may be lifted into the upper case position by a pin 7 carried on one end of a plunger 8 of a solenoid magnet 9. The magnet 9 (see Fig. 4) is mounted by means of a bracket 10 on the base 11. The plunger 8 passes through a coil

20 12. A screw 15, of which pin 7 is an integral part, has a nut 16 mounted thereon. It passes through a slot 13 in the upper end of the plunger 8 and by means of head 14 holds the plunger 8 within a recess of nut 16. The lower end of plunger 8 carries a finger 17 of insulating material adapted, when the magnet is energized, to press contact spring 18 into engagement with contact spring 19. By means of a bracket 20, the two springs, insulated from one-another, are mounted on the magnet 9.

25 Through the agency of levers 21 (Fig. 1) pivoted at 22, all keys like 6 operate a bail 23 pivoted at 24 and rotate it in a clockwise direction against the tension of a spring 25. The bail 23 extends under all the key levers associated with type bars so that whenever any one of these keys is depressed, the bail will move, through the agency of insulating pin 26, a contact spring 27 away from contact spring 28. These two contacts are insulated from one another and are mounted on a plate 29 fastened to base 11 by means of screws 31. The plate 29 has an embossing 30 which contacts with a plate 29' lying flat on the base 11 whereby the position of the contact springs with respect to bail 23 can be adjusted by means of screws 31.

30 Another set of contacts 32, 33 (Fig. 1) is similarly mounted by means of plates 34, 34' on base 11 by screws 35 in cooperative relation with space bar 36. Whenever the space bar 36 is depressed it presses through the agency of insulating pin 37 contact 32 into engagement with contact 33.

35 A third set of contacts 38, 39 is mounted on the base 11 by means of a bracket 40 (Fig. 2). A lever 55 pivoted at 43 may press these contacts into en-

gagement by an insulating member 41 carried at the end of arm 42 of the lever. A second arm 44 of this lever projects into the path of stop 45 held in position by means of spring 47 on toothed rack 46 provided on the back of carriage 1. This stop 45 also controls the left-hand margin or the position at which each new line normally starts. When the carriage is returned to begin a new line by means of handle 48 (or otherwise), the stop 45 will rotate lever 44 counter-clockwise, and cause arm 42 to close contacts 38, 39.

Two push buttons 51, 52 and a key 53 are mounted in housing 66 attached to base 11 at the left of the typewriter (see Fig. 6) and operate, respectively, contacts 54—55, 56—57 and 58—59.

All the parts of the typewriter are enclosed within a casing 49 which by means of legs 50 is positioned by pins 67 on base 11 so that the two sets of contacts 27—28 and 32—33 cooperate with bail 23 and space bar 36, respectively, and that the pin 7 engages the carriage 1, and that adjustable stop 45 engages lever end 44.

Current is supplied to magnet coil 12 (Fig. 7) through the secondary winding 61 of a transformer 60, the primary winding 62 of which is connected with the power mains.

Let us assume that the operator wishes to address a number of envelopes and that the address aforementioned is typical.

The operator will move key 53 into the "on" position closing contacts 58, 59.

With the carriage in its initial position (at the beginning of a line), an energizing circuit is closed for magnet 9 from the transformer secondary 61, over coil 12, conductor 64, contacts 38, 39, conductor 65, the normally closed contacts 56, 57 of unshift key 52, contacts 58, 59, and back to winding 61.

The magnet 9 will lift the carriage 1 into the upper case position and closes a locking circuit for itself over its now closed contacts 18, 19, the normally closed contacts 27, 28, resistance 63, contacts 51, 56, contacts 58, 59 and back to winding 61.

When the first key like 6 is depressed and operates a type bar, the upper case type will register with the platen. The first key struck will actuate bail 23 to open contacts 27, 28 and since the carriage has left its initial position, the contacts 38, 39 will be open and the magnet 9 becomes de-energized and the carriage 1 returns into the lower case position.

The following characters will all be printed while the carriage is in the lower case position. When, however, the space bar 36 is depressed after "Mr.", the contacts 32, 33 will be closed and close the circuit of magnet 9 over conductors 64 and 65, and contacts 56—57 and 58—59 and the magnet will lock up.

The letter "J" will be upper case, whereupon contacts 27, 28 will open the locking circuit and the rest of the word will be lower case.

It will thus be seen that the entire address can be written without touching the manual shift key

4. The following are examples of the kind of text, other than addressing, on which a typist may save time and effort by the application of this invention:

"Those present were: J. G. Abbot, H. G. Barnes, F. M. Crosley, J. J. Dorman, etc."

J. G. Stine, Pres.
C. C. Fish, V. P.
M. G. Ward, Sec. Treas.
F. G. Havard, Gen. Mgr.
S. M. Osborn, Prod. Mgr."

If at any time, while key 53 is "on," the operator wishes to disable the automatic shift, e. g., if the sign # is not desired before the street number, she can do so by depressing button 52. This will open contacts 56, 57 through which pass the energizing and locking circuits of coil 12.

If it is desired to write upper case at a time when normally a lower case would appear, e. g., when writing the name "McLean" instead of "Mc Lean," the operator depresses button 51, closing contacts 54, 55 which will close the circuit of coil 12 over the same path as contacts 32—33 or 38—39.

When the key 53 is in the "off" position, the contacts 58—59 are open and the shifting is controlled by keys 4 and 4a.

It should be noted that the application of this invention as here illustrated in no way interferes with the normal operation of the typewriter.

It will be obvious that while the invention is here disclosed as an attachment to a conventional typewriter it is applicable to a wide variety of typewriters and the like, and may be embodied in such machines otherwise than as an attachment, and that the control means here disclosed may be varied.

What I claim is:

1. A typewriter having a carriage, a keyboard of type operating keys, a spacing key, a case shift mechanism having upper and lower case positions for raising and lowering said carriage into corresponding positions, two sets of contacts, an electromagnet controlled by the contacts, for lifting said carriage into the upper case position, a connection between the spacing key and the first set of contacts for closing the latter upon each operation of the spacing key, a connection between the keys of the keyboard and the second set of contacts for opening the latter upon the operation of a key, an energizing circuit for said magnet closed upon each closing of the first set of contacts, and a locking circuit for said magnet including the second set of contacts.

2. A typewriter having a carriage, a keyboard of type operating keys, a spacing key, a case shift mechanism having upper and lower case positions for raising and lowering said carriage into corresponding positions, two sets of contacts, an electromagnet controlled by the contacts, an armature for said magnet for lifting said carriage into the upper case position, locking contacts operated by the armature, a connection between the spacing key and the first set of contacts for closing the latter upon each operation of the spacing key, a connection between the keys of the keyboard and the second set of contacts for opening the latter upon the operation of a key, an energizing circuit for said magnet closed upon each closing of the first set of contacts, and a locking circuit for said magnet including said locking contacts and the second set of contacts.

3. In a key operated typing machine having characters in two cases and a carriage adapted for movement in a letter space direction from an initial position and return to the initial position, an attachment comprising means to cause the first character typed in each initial position and the first character following a space to be from one case and all other characters from the other case.

4. In a machine of the character described, a keyboard of type operating keys, a spacing key, a

carriage adapted for movement in a letter space direction from an initial position and return to the initial position, a case shifting mechanism having upper and lower case positions, and means for moving the shifting mechanism into the upper case position in response to each actuation of the spacing key, and also whenever the carriage is returned to the initial position and for returning the shifting mechanism into the lower case position when the first type operating key is actuated.

5. A typewriter having a carriage adapted for movement in a letter space direction from an initial position and return to the initial position, a keyboard of type operating keys, a case shift mechanism having upper and lower case positions for raising and lowering said carriage into corresponding positions, two sets of contacts, an electromagnet controlled by the contacts for lifting said carriage into the upper case position, means for closing the first set of contacts whenever the carriage is returned to the initial position, a connection between the keys of the keyboard and the second set of contacts for opening the latter upon the operation of a key, an energizing circuit for said magnet closed upon each closing of the first set of contacts, and a locking circuit for said magnet including the second set of contacts.

6. A typewriter having a carriage adapted for movement in a letter space direction from an initial position and return to the initial position, a keyboard of type operating keys, a spacing key, a case shift mechanism having upper and lower case positions in which the carriage is lifted and lowered into corresponding positions, a shift key for controlling the raising and lowering of said carriage, three sets of contacts, an electromagnet controlled by the contacts, an armature for said magnet for lifting said carriage into the upper case position independently of the case shift key, locking contacts operated by the armature, a connection between the spacing key and the first set of contacts for closing the latter upon each operation of the spacing key, a connection between the keys of the keyboard and the second set of contacts for opening the latter upon the operation of a key, means for closing the third set of contacts upon each return of the carriage to the initial position, an energizing circuit for said magnet closed upon each closing of the first and third sets of contacts and a locking circuit for said

10 magnet including said locking contacts and the second set of contacts.

7. The combination with a typewriter having a carriage adapted for movement in a letter space direction from an initial position and return to the initial position, a keyboard of type operating keys, a spacing key, a case shift mechanism having upper and lower case positions in which the carriage is lifted and lowered into corresponding positions, a shift key for operating said mechanism, and means for returning the carriage to the initial position, of a base plate on which said typewriter is mounted, separate means on said base plate for lifting said carriage into the upper case position independently of the case shift key, a connection between the spacing key and said separate means, means for moving said separate means into the upper case position whenever the carriage is returned to the initial position, and a connection between the keyboard and said separate means to move it into the lower case position when a type operating key is actuated.

8. The combination of a typewriter having a carriage adapted for movement in a letter space direction from an initial position and return to the initial position, a keyboard of type operating keys, a spacing key, a case shift mechanism having upper and lower case positions in which the carriage is lifted and lowered into corresponding positions, a shift key for operating said mechanism, and means for returning the carriage to the initial position, of a base plate on which said typewriter is mounted, three sets of contacts and springs and an electromagnet controlled by the 25 contacts mounted on said base plate, an armature for said magnet for lifting said carriage into the upper case position independently of the case shift key, locking contacts mounted on said magnet and operated by the armature, a connection 30 between the spacing key and the first set of contacts for closing the latter upon each operation of the spacing key, a connection between the keys of the keyboard and the second set of contacts for opening the latter upon the operation of any key, means for operating the third set of contacts whenever the carriage is returned to the initial position, an energizing circuit closed for said magnet upon each closing of the first and third sets of contacts, a locking circuit for said 35 magnet including said contacts and the second set of contacts, and a fourth set of contacts for closing an energizing circuit for said magnet.

PAUL M. RAINES.
